END BRACE FOR VENETIAN BLIND
HEAD BARS

Hans K. Lorentzen, Montclair, N. J., assignor to
Lorentzen Hardware Mfg. Corp., New York,
N. Y., a corporation of New York

Application November 18, 1952, Serial No. 321,097

6 Claims. (Cl. 160—178)

1

This invention relates to Venetian blinds and, more particularly, to a head bar channel assembly and an end brace therefor.

A Venetian blind is essentially an assembly of superimposed articulated slats which are carried by a head bar extending across the top of the blind and on which is mounted mechanism for raising and tilting the slats of the blind. The head bar may be of the "enclosed head" type, in which the head bar is usually a sheet metal channel of U-shaped cross section, the free longitudinal edges of the channel being curled to form inturned hollow beads. Installation brackets, which are often secured to the jambs of the window frame, are customarily used to removably support the ends of the head bar.

In making blinds for particular windows, the head bars are not normally cut precisely to fit tightly into the space between the two installation brackets. Instead, the head bar is cut somewhat shorter to assure that it will conveniently enter the space between the brackets. This results in a more or less loose fit. Generally speaking, with ready-made or "stock" blinds, the head bars are usually made in incremental lengths of one inch throughout the most widely used range of sizes. Thus, the head bar may be as much as one inch shorter than the maximum mounting space afforded by the installation brackets of a particular installation.

To prevent endwise shifting of the head bar after it has been positioned on the installation brackets, to prevent the possibility of an end of the head bar slipping off of one of the brackets, and to brace the top of the head bar, the head bar may be provided with end braces having one or more resilient fingers which take up the excess space and keep the head bar centered. Such an end brace is shown in U. S. Patent 2,455,135.

The end brace of the present invention is formed of a single length of wire which has an intermediate portion for spanning between the beads of the head bar and a bead-engaging portion at each end of the intermediate portion. At least one end of the wire projects on the side of the intermediate portion opposite to the bead-engaging portions to form a resilient finger which projects outwardly beyond the end of the head bar. As compared to the prior art braces, the present end brace is less expensive; also head bars equipped with it can be more rapidly installed.

Among the objects of the present invention are to provide a very inexpensive end brace having at least one resilient finger operable to position

2
a head bar with respect to an installation bracket, to provide an end brace which can be rapidly manufactured, and to provide an end brace which can be easily installed in a head bar and which automatically adjusts itself to the spacing requirements of the head bar with respect to the installation brackets.

My invention is clearly defined in the appended claims. In the claims, as well as in the description, parts may at times be identified by specific names for clarity and convenience, but such nomenclature is to be understood as having the broadest meaning consistent with the context and with the concept of my invention as distinguished from the pertinent prior art. The best forms in which I have contemplated applying my invention are illustrated in the accompanying drawings forming part of this specification, in which:

20 Fig. 1 is a perspective view of a portion of a Venetian blind including a head bar and an installation bracket shown in exploded relation thereto.

25 Fig. 2 is a plan view of one form of end brace per se, in accordance with the present invention.

Fig. 3 is an isometric view of an end of a head bar channel and the end brace of Fig. 2 in exploded relation thereto.

30 Fig. 4 is a view similar to Fig. 3 but showing the end brace assembled with the head bar channel.

Fig. 5 is a fragmentary sectional view taken generally on the line 5—5 of Fig. 4.

35 Fig. 6 is a plan view of a second form of end brace, in accordance with the present invention.

Fig. 7 is a plan view of a third form of end brace, in accordance with the present invention.

The Venetian blind 10 is of the "enclosed head" type, having a head bar 11 formed of a sheet metal channel of U-shaped cross section. The free longitudinal edges 12, 12 of the channel 11 are inturned to form hollow beads 14, 14. Operating mechanism (not shown) for tilting and lifting the slats of the blind is mounted within the channel 11.

The blind 10 may be installed as a unit in a pair of installation brackets, one such bracket 15 being shown in Fig. 1. The installation brackets 15 may be of any suitable construction, the bracket shown being one that is available on the market. Each bracket 15 is provided with a body 16 having a side plate 17 and bottom flange 18. A pivoted retainer 19 closes the front of the bracket.

When installing the blind, the retainer 19 is opened to admit the head bar 11 of the blind 10, the head bar 11 being moved rearwardly and the ends thereof resting on the bottom flanges of the brackets. In a typical installation the head bar will not completely span the space between the side plates 17 of the two brackets, for the reasons that have been pointed out.

After installation of the head bar, there will be a tendency for the head bar to shift longitudinally within the brackets upon the operation of the blind. To prevent this undesirable shifting, to keep the head bar centered with respect to the brackets, and to brace the channel from front to back, an end brace of suitable construction is used. As shown an end brace 20 is inserted in each end of the channel 11, each brace 19 being provided with a resilient finger 21 to bear against the side plate of the adjacent bracket 15, thereby centering the head bar with respect to the installation brackets and eliminating endwise movement of the head bar 11.

The end brace 20 is formed from a single length of springy wire. It has been found that hard steel wire having considerable resiliency and capable of yielding over a considerable range within the elastic limit, and having a diameter on the order of $7/1000$ of an inch is suitable for this purpose.

The central zone of the wire constitutes an intermediate portion 22 spanning between the beads 14, 14 of the channel 11. This zone may be provided with a loop 23, see Fig. 3, the purpose of which will be explained later. The portions of the wire at the ends of the intermediate portion 22 are bent at right angles to the intermediate portion 22 and then back upon themselves in spaced relation to form a pair of resilient bead-engaging portions 24, 24, which are proportioned to telescope within and frictionally engage the inner walls of the beads 14, 14 in resilient manner.

One of the terminal ends of the wire projects on that side of the intermediate portion 22 which is opposite to the bead-engaging portions 24, 24 at an acute angle to the intermediate portion 22 to form the resilient finger 21. If desired, both of the terminal ends may so project to form two fingers, as shown in Fig. 6. The tip 26 of the wire may be bent slightly toward the intermediate portion 22 to form a smooth rounded end on the finger.

During assembly of the head bar, an end brace 20 is installed in each end of the head bar channel 11 by inserting the bead-engaging portions 24, 24 into the hollow beads 14, 14. The bead-engaging portions 24, 24 are resilient, and the brace may be assembled by driving or pressing these portions into the ends of the beads 14, 14, after which they will frictionally engage the inner walls of the beads and resist displacement therefrom.

With an end brace 20 installed in each end of the channel 11, the blind is inserted into the installation brackets. In inserting the head bar, it has been found desirable to have that end of the brace 20 which is provided with the finger 21 located towards the bracket, so that upon movement of the head bar into the bracket, the inclined portion of the finger 21 will be resiliently cammed toward the end of head bar as required to put the head bar in place on the installation brackets. In this way these fingers automatically adjust themselves to the spacing requirements of the head bar.

If, upon installation of the blind in the brackets, it is found that there is excessive space between the front wall of the head bar 11 and the retainer 19 of the bracket 15, the blind can be removed and the sides of the channel pulled apart sufficiently to collapse the loop beyond its elastic limit. In this way the loop 23 provides for lengthening of the intermediate portion 22 for effectively increasing the width of the channel to make a snugger front-to-back fit within the brackets 15. Conversely, if the channel is slightly wider than the brackets so as to prevent closing of the retainer 19, the loop 23 will permit the length of the intermediate portion 22 to be shortened. This can be accomplished by pushing the side walls of the channel together, the excess wire going into increasing the size of the loop 23. It will be seen that this end brace provides for elimination of both lengthwise and transverse movement of the head bar within the brackets 15.

As before mentioned, if desired, the brace 20 may be provided with two fingers 21, 21 rather than just one, and also the loop 23 may be omitted from the intermediate portion 22. An end brace of such form is shown in Fig. 6.

Fig. 7 shows an additional alternate form of the brace wherein one of the bead-engaging portions 24' of the brace 20' is formed by bending the wire at right angles to the intermediate portion 22' and then inwardly and back upon itself in spaced relation, with the end portion of the wire continuing on to form an arcuate resilient finger 21' functioning similarly to the finger 21 above described. The end brace 20' is assembled and utilized in the same manner as described for the end brace 20.

I claim:

1. An end brace for a channel-shaped Venetian blind head bar having its free longitudinal edges formed into hollow beads, said brace comprising a single length of springy wire having an intermediate portion adapted to span between the beads of the channel and having portions at the ends of the intermediate portion that are bent at right angles to the intermediate portion and then back upon themselves in spaced relation to form resilient bead-engaging portions adapted to frictionally engage the inner walls of the beads, at least one of the terminal ends of the wire projecting on that side of the intermediate portion which is opposite to the bead-engaging portions to form a resilient finger.

2. An end brace for a channel-shaped Venetian blind head bar having its free longitudinal edges formed into hollow beads, said brace comprising: a length of springy wire having an intermediate portion adapted to span between the beads of the channel and having bead-engaging portions adapted to telescope within the beads and frictionally engage the inner walls thereof, at least one of the terminal ends of the wire projecting on that side of the intermediate portion which is opposite to the bead-engaging portions to form an angularly projecting resilient finger.

3. An end brace for a channel-shaped Venetian blind head bar having its free longitudinal edges formed into hollow beads, said brace comprising: a single length of springy wire having a straight intermediate portion adapted to span between the beads of the channel, the intermediate portion being provided with a loop adapted to permit adjustment of the length of the intermediate portion, and the wire having portions at the ends of the intermediate portion that are bent at right

angles to the intermediate portion and then back upon themselves in spaced relation to form bead-engaging portions adapted to frictionally engage the inner walls of the beads, the terminal ends of the wire projecting on that side of the intermediate portion which is opposite to the bead-engaging portions to form resilient fingers.

4. An end brace for a channel-shaped Venetian blind head bar having its free longitudinal edges formed into hollow beads, said brace comprising: a single length of springy wire having an intermediate portion adapted to span between the beads of the channel, the intermediate portion being provided with a loop adapted to permit adjustment of the length of the intermediate portion, and the wire having portions at the ends of the intermediate portion that are bent to form resilient bead-engaging portions adapted to frictionally engage the inner walls of the beads, at least one of the terminal ends of the wire projecting on that side of the intermediate portion which is opposite to the bead-engaging portions to form an angularly projecting resilient finger.

5. In a Venetian blind head bar assembly, a head bar channel having its free longitudinal edges inturned to form hollow beads; and an end brace comprising a length of wire having an intermediate portion spanning the space between the beads and having portions at the ends of

the intermediate portion that are bent at right angles to the intermediate portion and then back upon themselves in spaced relation to form bead-engaging portions that are telescoped within the beads and frictionally engage the inner walls thereof, at least one terminal end of the wire projecting on that side of the intermediate portion which is opposite to the bead-engaging portions to form a resilient finger projecting beyond the end of the channel.

6. In a Venetian blind head bar assembly, a head bar channel having its free longitudinal edges inturned to form hollow beads; and an end brace comprising a length of wire having an intermediate portion spanning the space between the beads and having portions at the ends of the intermediate portion that are bent at right angles to the intermediate portion and then back upon themselves in spaced relation to form resilient bead-engaging portions that are telescoped within the beads and frictionally engage the inner walls thereof, the terminal ends of the wire projecting on that side of the intermediate portion which is opposite to the bead-engaging portions to form a pair of converging resilient fingers projecting beyond the end of the channel.
